UNITED STATES PATENT OFFICE.

LEO HAUBERT, OF BEGGS, OKLAHOMA, ASSIGNOR OF ONE-THIRD TO JOHN C. BENNETT AND ONE-THIRD TO JOHN A. WOLFE, BOTH OF TULSA, OKLAHOMA.

CASING HEAD FOR OIL WELLS.

Application filed January 19, 1921. Serial No. 438,429.

To all whom it may concern:

Be it known that I, LEO HAUBERT, a citizen of the United States, residing at Beggs, in the county of Okmulgee and State 5 of Oklahoma, have invented new and useful Improvements in Casing Heads for Oil Wells, of which the following is a specification.

This invention has reference to casing 10 heads for oil wells, and its object is to provide a casing head adapted to various sizes of tubing and provided with a top which may be readily taken off when the first joint of the tubing is applied, and whereby 15 oil, which may flow out from the tubing when unscrewed will find its way back into the well or may be diverted into a suitable reservoir to prevent waste.

In accordance with the invention, the casing 20 head has a bore of upwardly flaring contour, to receive spider devices seating in the casing head and serving to sustain the weight of the tubing.

In conjunction with the casing head and 25 well tubing, there is provided a device through which the tubing extends and which is designed to divert fluid which may be discharged from a joint of tubing when unscrewed from the tubing below it, thus 30 protecting workmen from the outflowing fluid and causing such fluid to flow back into the well or into a suitable reservoir.

The invention will be best understood 35 from a consideration of the following detailed description taken in connection with the accompanying drawings forming part of this specification, with the understanding, however, that the invention is not confined to any strict conformity with the 40 showing in the drawings, but may be changed and modified so long as such changes and modifications mark no material departure from the salient features of the invention as expressed in the appended 45 claims.

In the drawings:

Figure 1 is an elevation of a casing head 50 constructed in accordance with the invention, and showing some parts in section.

Figure 2 is a vertical diametric section through the structure shown in Figure 1.

Figure 3 is a plan of the structure shown in Figure 2, but omitting the casing head top.

Figure 4 is a view similar to Figure 2,

but showing some parts removed and the fluid deflector in place.

Figure 5 is a plan view of the deflector.

Figure 6 is a view similar to Figure 2, but showing the casing head top in place 60 and a coupling of the tubing resting thereon.

Figure 7 is a plan view of the structure shown in Figure 6, but with the casing top omitted.

Figure 8 is a plan view of a spider similar to that shown in Figure 2.

Figure 9 is an elevation of the spider shown in Figure 8.

Figure 10 is a plan view of the form of spider shown in Figure 7.

Fig. 11 is a view partly in elevation and partly in section of a form of spider slightly different from that shown in Fig. 10.

Referring to the drawings, there is shown the upper end of a well casing 1, in 75 Figures 1, 2, 4 and 6, and this casing has its upper end screw-threaded as indicated at 2, to receive a casing head 3, comprising a ring 4 threaded to screw onto the upper end of the casing. From the ring 4, there rises 80 a flaring head 5, in the upper end of which there is produced an annular groove 6, with a basic or flare portion 7, provided with a shallow groove 8. The groove 6 contains a packing ring 9 on which is seated 85 a casing head top or cover 10, held in place by set screws 11 extending through the outer edge of the casing head, whereby the cover may be securely fastened in place, or may be loosened for removal.

Where the ring 4 screws onto the casing 1, it is provided with an inwardly directed flange 12, forming a ledge designed to support certain structures. Seated on the ledge 12 is a spider 13, provided with a hub 14 95 and radial arms 15 and 16, the latter terminating in oppositely directed lugs 17 conforming in flare to the inner wall of the flaring head or extension. The lugs 17 are traversed by set screws 18, by means of 100 which the spider is firmly held in position.

The hub 14 is shown as traversed by a well tube 19 rising through the spider 13 and through the casing head top 10, with the tubing supported by any appropriate 105 device, indicated in dotted lines at 20. Tapped through the sides of the casing head are pipes 21, whereby gas or the like may be conveyed from the casing head to some point of disposal. There is another 110

spider 22, shown separately in Figure 10, and this spider has arms 23 radiating from a hub 24 with two of the arms 23^a having oppositely disposed lugs 25 at their outer ends fitted to the inner wall of the flaring part 5 of the head to be secured in place by bolts 18^c. The spider 22 has a basic plate 26 of a size to rest upon the ledge 12 with interposed packing 27, shown in Figure 6, whereby fluid discharged from a removed tubing section is caught in the receptacle formed by the spider 22 and the flaring walls of the casing head. By forming the bottom 26 of the spider 22 separately from the body of the spider, and securing it in place by screws 28, a gasket or washer 29 is secured in place in the lower end of the hub 24, so that the tubing 19 may be readily passed through the gasket with the latter hugging the tubing and at the same time permitting the usual tubing couplings 30 to pass through the gasket. By this arrangement, fluids may be caught in the casing head and conducted by way of pipes 21 to some point of disposal, instead of permitting the fluids to flow back into the well or to waste.

The spider 22^a, shown in Fig. 11, is a slightly modified form of the spider 22, wherein the bottom 26^a is made integral with the hub 24^a which is provided with a shoulder 24^b against which the gasket 29 is secured.

The pipes 31 permit gas to be taken from the well to be used for fuel to furnish power while pulling the tubing and the gasket or washer 29 in the lower end of the hub 24 is to hold the gas in the well while the tubing is being pulled and the gas taken from the well through the pipes 31, as stated. Sometimes oil will commence to flow through the casing 1, while the tubing is being pulled, in which case the oil will go through the pipes 31 of the casing head to a storage tank instead of overflowing the derrick, as heretofore, and being wasted as well as being dangerous on account of catching fire from an adjacent boiler furnace, as sometimes occurs.

When the tubing is pulled, and a section is unscrewed from the next lower one, workmen are often deluged by the escaping oil or other liquid, and in order to prevent this there is provided a deflector 32 shown separately in Fig. 5. The deflector comprises two members hinged together at one side and furnished with handles 33 by means of which the two members of the deflector may be spread open or closed together and when spread open are sufficiently separated to permit application sidewise to the tubing 19. To facilitate the application of the deflector, a spring 34 is lodged between the handles 33 and a layer of felt 35 or some other similar material is applied about that portion 65 of the deflector which grips the tubing.

Furthermore, the lower end of the deflector is in the form of an apron 36 with an in-turned flange 37, so that when the pipe or tubing section is unscrewed and the oil drops, the tendency will be to divert the oil toward the interior of the casing head so that it will gravitate into the well.

The deflector shown in the drawing forms the subject matter of a separate application filed by me January 19, 1921, Serial No. 438,430.

What is claimed is:—

1. A casing head comprising a ring adapted to be secured to the upper end of a well casing and provided with a flaring, rising extension, a closure for the larger end of the extension, ducts leading from said extension, and a spider having the ends of its arms seated on the flaring extensions of the ring.

2. A casing head comprising a ring adapted to be secured to the upper end of a well casing and provided with a flaring, rising extension, a closure for the larger end of the extension, ducts leading from said extension, and a spider adapted to seat in the said extension and having a hub to be traversed by the well tubing.

3. A casing head comprising a ring adapted to be secured to the upper end of a well casing and provided with a flaring, rising extension, a closure for the larger end of the extension, ducts leading from said extension, and a spider adapted to seat in the said extension and having a hub to be traversed by the well tubing, said spider having arms terminating in lugs for attachment to the inner wall of the extension.

4. A casing head for oil or gas wells, comprising a ring adapted to be secured to the upper end of the well casing and provided with a flaring, rising extension having a seat at its upper end with a groove or recess thereabout, a casing head top adapted to the seat and provided with a passage for the well tubing, and means for fastening the casing head top to the casing head within the groove or seat.

5. A casing head comprising a ring adapted to be secured to the upper end of a well casing and provided with a flaring, rising extension, a spider adapted to seat in the flaring casing head and provided with a hub to be traversed by the well tubing, ducts leading from the upward extension of the casing head, a basic plate forming the bottom of the upward extension of the casing head above the ring, and a spider to which the basic plate is secured and provided with means for in turn securing said spider to the casing head.

6. A casing head comprising a ring adapted to be secured to the upper end of a well casing and provided with a flaring, rising extension, a spider adapted to seat in the

flaring casing head and provided with a hub to be traversed by the well tubing, ducts leading from the upward extension of the casing head, a basic plate forming the bottom of the upward extension of the casing head above the ring, and a spider to which the basic plate is secured and provided with means for in turn securing said spider to the casing head, said casing head also being provided with a casing head top covering the casing head and provided with means for securing it in place.

5 10 7. A casing head, comprising a ring adapted to be secured to the upper end of a well

15 casing, a closure for the upper end of the casing head, another closure for the upper end of the well casing, a hub and spider located within the head and carried thereby, a gasket or washer carried by the spider in surrounding relation to the well 20 tubing, and ducts carried by the head in communication with the well casing below the gasket.

25 In testimony, that I claim the foregoing as my own, I have hereto affixed my signature.

LEO HAUBERT.
